UNITED STATES PATENT OFFICE.

ELAM D. PATTERSON, OF COSHOCOTON, OHIO, ASSIGNOR TO JAMES B. CLOW AND SONS, OF CHICAGO, ILLINOIS, A CORPORATION OF ILLINOIS.

MACHINE FOR RAMMING MOLDS AND THE LIKE.

Application filed October 16, 1926. Serial No. 141,919.

This invention relates to tamping or ramming devices particularly designed for ramming pipe and other cylindrical molds although in its broader aspects, it is adaptable 5 in a large variety of forms for use in other connections. Herein the invention will be disclosed in a device constructed and arranged for foundry use in tamping or ramming vertical, cylindrical molds in which 10 iron pipe and the like is to be cast.

My invention is designed to overcome the difficulties incident to hand rammed molds and has as one of its principal objects the provision of a device capable of automatically 15 performing the many necessary steps in properly tamping or ramming molds and includes arrangements whereby all portions of the sand of the mold will be compacted to substantially the same degree of density 20 about the mold and longitudinally thereof.

Another object is to provide a machine of the character described with means for absorbing the reactionary shocks imposed on the ramming mechanism and tended to be 25 transmitted to the support by the impact or deceleration of the rams or peens at the ends of their strokes.

A further object is to provide a machine of the character specified with a plurality of 30 ram rods and peens adapted to ram two or more preferably diametric portions of a cylindrical mold or the like simultaneously and with mechanism adapted to advance one or both of the ram rods and peens to 35 successive ramming positions about the mold.

Still further objects include the provision of adjustments whereby the ramming machine may be adapted to ram circular or 40 cylindrical molds of different diameters or of different thicknesses, to provide such a device with an automatic stabilizing device adapted to prevent reactionary forces, set 45 in motion by deceleration or impact of the ramming mechanism at the ends of the strokes of the ram rods, from tending to throw the ramming device out of alignment or twisting the end thereby straining it, to 50 provide a counterbalanced support for the ramming mechanism and to provide a ramming machine of simple and reasonably inexpensive construction possessing the advantages heretofore enumerated as well as those which will be or should become readily 55 appreciated from the succeeding disclosure.

Numerous other objects as well as the adaptability of my invention to other fields of use other than that in which I will describe a preferred embodiment, will be apparent from the following description and 60 claims and from the drawing in which:

Fig. 1 is a front elevational view of a pipe mold ramming machine constructed in accordance with the preferred form of my invention, 65

Fig. 2 is a transverse sectional view taken on the line 2-2 of Fig. 1,

Fig. 3 is a fragmentary longitudinal sectional view taken along the line 3-3 of Fig. 2, 70

Fig. 4 is a transverse sectional view taken along the staggered line 4-4 of Fig. 1,

Fig. 5 is a fragmentary sectional view taken along the line 5-5 of Fig. 1, and 75

Fig. 6 and Fig. 7 are top plan and end elevational views, respectively, of the ratchet dog yoke, a detail of a preferred form of mechanism for effecting rotation of the ram rods to various positions about a cylindrical or circular mold. 80

The tamping or ramming apparatus illustrating my invention is supported from an overhead girder or frame 2 on which pulleys 3 and 4 are revolvably mounted in bearings 5 and 6 by means of a cable or the like 7, trained over the pulleys 3 and 4 and attached at one end 8 to a yoke 9 and at its other end to weights 11 sufficient in number to counterbalance the weight of the mechanism which will be hereinafter more particularly described. The yoke 9 is provided with bolts 12 at its lower ends and on the lower ends of these bolts, nuts 13 secure plates 14 between which and the bottom face of a yoke guide 15 springs 16 are positioned. The yoke 15 has arms 17 which rest on the top of springs 16 which are drilled for sliding movement on the bolts 12 for a purpose to be hereinafter described. At their outer ends, the arms 17 are forked to receive the shanks of T guides 18 secured to the girder or frame member 2 so that the ramming machine may be vertically raised or lowered in guided position as will be apparent. 95

The yoke guide 15 is provided with a central hub through which the casing 19, within which any reciprocating prime mover such as, a stem or an air piston or an electrical solenoid is housed, is secured against 100 105 110

rotary or longitudinal movement although it may be made adjustable therethrough if desired. The casing 19 projects below the hub of the yoke arm 15 and is rigidly attached in any suitable manner to a stationary casing 21 preferably slotted on opposite sides as shown at 22 in order that a cross head 23 secured between collars 24 on a piston rod 25 reciprocal within the casings 21 and 19 may slide therein and reciprocate with the piston rod as the latter is reciprocated by the prime mover.

The cross head 23 is extended outwardly beyond the outer faces of the casing 21 to provide clearances between the outer surface of the casing and a channel ring 26 which is secured to the cross head by bolts 27 and nuts 28. This channel ring 26 has upper and lower flanges 29 and 31 between which arcuate members 32 are slidably mounted for rotation about the axis of the piston rod 25 and casing 21. This arcuate member 32 is provided with a boss 33 which is drilled on its radius of curvature and on a radius of the casing 22 and piston rod 25 and, as will be apparent, on the same diameter of these latter mentioned parts for the reception of trunnion bearing pins 34. A yoke member 35 is provided with diametric bosses 36 which are also drilled to receive the trunnion bearing pins 34 and while generally of circular form has parallel spaced arms 37 and 38 on either side of a diameter 90° about the axis from the axis of the trunnion bearing pins 34. The pairs of arms 37 and 38 are as a consequence of the forementioned construction oppositely disposed and each arm of each pair is drilled preferably at two or more places 39 for the reception of a pivot pin 41 at different distances from the axis of the reciprocating piston rod 25. From the foregoing, it will be apparent that the yoke ring 35 is free to swing to some extent about or on the trunnion bearing pins 34 while by reason of the arcuate members 32, it may be swung about the axis of the piston rod 25 to any position thereabout and at the same time be reciprocated upon reciprocation of the piston rod.

The pins 41 projecting through the arms 37 and 38 pivotally support ram rods 42 for relatively free swinging movement in order that the arcuate peens 43 on their lower ends (only one peen shown) may give relatively to one another in case the surface with which they contact or impact is irregular whereby the ramming pressure and therefore the degree of compaction of the sand or other material in the mold will be equalized. In order, however, that the yoke ring 35 and the ram rods 42 may not swing unnecessarily about their pivots pendulum-wise, a damper or stabilizer designated 44 of generally cylindrical form for rotation

with the yoke ring 35 is secured against rotation to the outer ends of trunnion pins 34 which are also secured against rotation in the bosses 33 of the arcuate members 32. On a diameter parallel to the diameter of the rod 25 passing medially between the arms 38 and 37, the stabilizer 44 is provided with upstanding projections 45 adapted to limit the downward movement of either pair of arms 37 and 38 by contacting with the bottoms 46 of the web portion of the ring 35 between the arms 37 and 38.

It will now be apparent that upon reciprocation of the piston rod 25 under the influence of the prime mover, the ram rods 42 will be reciprocated for tamping or ramming engagement of the peens 43 with the surface of the sand or other material to form the mold and that inequalities in the surface of the material being rammed will be compensated for by the equalizing device including the yoke ring 35 and the several pivotal connections. The shock of impact of the peens 43 with the material of which the mold is being formed will be absorbed by the springs 16 and can not be transmitted to the guideways 18 or to the frame or girder and thus to the building or other structure in which the rammer is located. It will also be appreciated that if desired, the ramming mechanism may be considered as complete for use as so far described and the yoke ring 35 and thus the ram rods 42 and their peens 43 may be swung about the axis of the reciprocating rod 25 for ramming all portions of a cylindrical or circular mold or the like. However, I desire to have the ram rods and peens moved to various successive positions about the mold automatically and for this purpose, I have provided mechanism which will now be described.

The casing 21 is extended downwardly below the stabilizing member 44 and has thicker walls at this lower end which provide a reduced internal bore as shown at 47 in Figs. 3, 4, and 5 for the reception of a cross head 48 having circumferential guide surfaces 49 for sliding within the bore 47. The cross head 48 is provided with a projection 51 which passes through a slot 52 extending longitudinally of the lower end of the casing so that it may reciprocate with the rod and is secured on the end of the rod by a nut 53 threadedly engaging a threaded reduced end portion of the rod designated 54. The projection 51 of this cross head has a reduced shank portion 55 which is threaded at its outer end to receive a nut 56 which secures a cam roller 57 from displacement from the reduced portion 55 on which it is rotatably mounted. As the piston rod 25 reciprocates carrying the cross head 48 with it, the cam roller 57 is adapted to contact with a lever projecting into its path as will be described infra.

The extreme lower end of the casing 21 as indicated at 58 is surrounded by a collar 59 which is rigidly but removably secured thereto forming a thrust bearing for a rotatable ratchet ring supporting member and yoke 61. The member 59 has oppositely extending yoke arms 62 which are slotted as shown at 63 in order that the ram rods 42 may pass through them with freedom for side to side swinging movement toward and from one another. Preferably on a diameter transverse to the diameter forming the medium line of the arm 62, the member 61 is provided with brackets 64 through which 10 bolts secured by nuts 65 pass for securing ratchet ring 66 thereon. The member 61 is provided with an upwardly facing shoulder 67 adapted to abut against and project radially outward beyond a cooperative shoulder 20 formed on the lower end 58 of the casing between which and the thrust collar 59 the member 61 is mounted for rotation.

Between that portion of the shoulder 67 extending radially outwardly beyond its cooperative shoulder formed on the casing and a circumferential shoulder 68 formed on the casing, a ring member 69 is rotatably mounted and at the rear side of this ring, bosses 71 are provided and drilled with registering openings on an axis transverse to the axis of the ring and tangential to its circumference for the reception of a hinge pin 72 which the substantially parallel arms 73 of a ratchet engaging dog yoke are hinged. 30 The ratchet dog carrying yoke is best illustrated in detail in Figs. 6 and 7. It is provided intermediate its arm 73 with a dog tooth projection 74 and a pivot pin opening 75 for a purpose to be hereinafter described. 35 With the foregoing description, the reader will appreciate that the tooth of the dog 74 is adapted to engage with the teeth 75' of the ratchet ring 66 and that upon counterclockwise movement of the dog and its yoke, the ring 69 and the member 61 will be rotated in an anticlockwise direction when the tooth 74 is engaged with and behind one of the teeth 75'. It will also be obvious that since the dog carrying yoke member is hinged to the ring 69 on the opposite side from the tooth 74 that the tooth 74 through its bevelled face 76 will ride over one or more teeth of the ring 66 in a clockwise direction for reengagement behind some successive tooth of the ratchet ring. 55

In order to move or rather to oscillate the dog carrying yoke, I have provided a cup member 77 bored out as shown at 78 for the reception of a ball 79 slightly less in diameter 60 and provided with a projecting lug 81 pivoted on a pin 82 secured by a nut 83 in the hole 75 provided in the dog carrying yoke member. Thus the cup member 77 is free to pivot on the pin 82 for a purpose which 65 will be understood as the description pro-

ceeds. The ball 79 is secured on one end of a lever 84 pivoted at 85 on a pivot pin 86 projecting through a boss 87 formed on one side of the casing 21. The opposite end 88 of the lever 84 is curved substantially as 70 shown in Fig. 1 into the path of cam roller 57 so that when the piston rod 25 moves upwardly, the cam roller will engage this end of the lever and move the same about its pivot 85 and thereby oscillate the dog carrying yoke member in a counterclockwise direction. The return of the lever 84 is enforced by a spring 89 which at one end is engaged as shown at 91 about the lower portion of the lever 84 and at its other end in 80 the pivot pin 86 while an abutment ring or washer 92 is placed over the end of the pivot pin 86 and between the spring and a cotter pin or the like 93 inserted through an opening in the end of the pivot pin, while movement of the lever 84 in a clockwise direction is limited by an adjustable stop member 94 secured to the casing 21, 85

While it is believed that the operation of the illustrated embodiment of my invention will be clear to the reader from what has been stated, I will briefly set it forth. Upon reciprocation of the piston rod 25, the cross head 23 will be actuated to reciprocate the ram rods 42. Upon every upward stroke of the piston rod, the cross head 48 through its cam roller 57 will rock the lever 84 about its pivot 85 and through the ball 79 and its socket in the cup member 77 will rotate the ratchet ring 66 to the extent of one or more teeth dependent upon the length of movement during which the cam roller and lever 88 are engaged. As the piston rod descends with the cross head 48, the spring 89 will return the lever to its initial position 105 against the adjustable abutment 94, the hinge dog carrying yoke swinging about its pivots in substantially vertical and horizontal planes to permit the dog 74 to ride over the teeth and to the end of its movement to 110 there engage behind some successive tooth for another like movement. The operation is entirely automatic and the mold will be adequately rammed at all points of its circumference and progressively upward as the sand is poured therein. Properly balancing the weight of the ramming mechanism with weights 11, the ramming mechanism will gradually work itself upward in the mold 115 until the whole has been properly rammed. 120 Manual assistance may be almost entirely avoided.

While I have described and illustrated a preferred embodiment of my invention and have pointed out some of the novelties in its construction, arrangement and use, it will be understood that it is susceptible of modifications and variations of construction bearing little or no resemblance to that illustrated and described and I do not wish therefore 125 130

to be limited other than by the spirit of the invention and the scope of the appended claims.

I claim:

5. 1. In a ramming machine, a ram rod, means independent of the mold for automatically imparting motion to said rod in two directions transverse to one another simultaneously, and means rendered operative by irregularities of the material being rammed for moving said rods in a third direction.
10. 2. In a ramming machine, a ram rod, automatic means independent of the mold for imparting motion to said rod in two directions transverse to one another, and means rendered operative by irregularities in the surface of the material being rammed for moving said rods in a third direction.
15. 3. In a ramming machine, a ram rod mounted for reciprocation and swinging movement about its axis of reciprocation and about an axis transverse to said axis of reciprocation and means for automatically reciprocating and swinging said rod about its axis of reciprocation simultaneously.
20. 4. In a ramming machine, a pair of spaced ram rods simultaneously reciprocal, means for automatically reciprocating said rods, and means for substantially equalizing the effective ramming pressure of said rods.
25. 5. In a ramming machine, a pair of spaced ram rods, means for imparting reciprocatory motion to said rods and means including a pivot connection between said motion imparting means and rods, for adjusting said rods to inequalities in a surface being rammed.
30. 6. In a ramming machine, a plurality of peens, means for projecting said peens simultaneously toward a surface of material to be compacted and means for substantially equalizing the effective ramming pressure of said peens.
35. 40. 7. In a ramming machine, a plurality of peens, means for reciprocating said peens simultaneously toward a surface of material to be compacted, and means for substantially equalizing the effective ramming pressure of said peens.
45. 8. In a ramming machine, a pair of spaced ram rods, means for automatically reciprocating said rods and for moving said rods to a series of ramming positions, and means for substantially equalizing the effective ramming pressure of said rods at any ramming position.
50. 9. In a ramming machine, a pair of spaced ram rods, automatic means for imparting reciprocatory motion to said rods and for moving said rods to a series of ramming positions, and means, including a pivot connection between said automatic means and rods, for adjusting said rods to inequalities in a surface being rammed.
55. 10. In a ramming machine, a plurality of peens, automatic means for reciprocating said peens simultaneously toward and from a surface of material to be compacted and for moving said peens to a series of compacting positions, and non-resilient means whereby said peens may automatically adjust themselves to inequalities of said surface upon contact therewith.
60. 11. In a ramming machine, a pair of spaced ram rods simultaneously reciprocal, means for automatically imparting motion to said rods in a plurality of directions, said directions being transverse to one another, and means for substantially equalizing the effective ramming pressure of said rods on contact with a surface to be compacted.
65. 12. In a ramming machine, a plurality of peens, means for automatically imparting motion to said peens in a plurality of directions, said directions being transverse to one another, for compacting material, and non-resilient means whereby said peens are automatically adjusted relatively to one another to compensate for inequalities in the surface of the material being compacted upon contact with such surface.
70. 13. In a ramming machine, a ram rod, means automatically operative for reciprocating said rod, means automatically operative in conjunction with said reciprocating means for moving said rod in a curved path to a series of ramming positions in succession, a vertically movable non-rotatable support for said rod, and a shock absorber interposed between said rod and said support.
75. 14. In a ramming machine, a ram rod, means for automatically imparting motion to said rod in a plurality of directions, said directions being transverse to one another, a support for said motion imparting means and rod, and means between said motion imparting means and said support for absorbing shocks tended to be transmitted to the support from said rod.
80. 15. In a ramming machine, a pair of stationary guides in spaced relation, a cross-arm slidably mounted on and between said guides, a ramming mechanism carried by said cross-arm, means for moving said cross-arm to various positions with respect to said guides, and shock absorbers interposed between said cross-arm and said moving means.
85. 16. In a ramming machine, a pair of substantially rigid guides disposed in parallel spaced and stationary relation to one another, a cross-arm slidably and non-rotatably associated with said guides, a ramming mechanism having a reciprocable part secured to said cross-arm, means for moving said cross-arm along said guideways in one direction, and resilient means interposed be-

tween said cross-arm and moving means for absorbing shocks resulting from the reciprocation of said part.

17. In a ramming machine, a pair of spaced ram rods, means for reciprocating said rods simultaneously, and means for moving said rods to a plurality of successive positions of reciprocation by a step by step movement.

18. In a ramming machine, a pair of spaced ram rods, means for reciprocating said rods, and means for moving each of said rods in a curved path by a step by step movement.

19. In a ramming machine, a ram rod, means for reciprocating said rod, and means operated by reciprocation of said rod for moving the rod in a curved path.

20. In a ramming machine, a pair of spaced ram rods, means for reciprocating said rods, and means operative upon reciprocation of said rods for moving said rods in substantially circular paths.

21. In a ramming machine, a pair of spaced ram rods, means for reciprocating said rods, and means operative upon reciprocation of said rods for moving said rods in substantially circular paths by a step by step movement.

22. In a ramming machine, a reciprocable member, means for reciprocating said member, means pivotally associated with said member and movable therewith and a pair of ram rods pivoted to said pivotally associated means and movable therewith.

23. In a ramming machine, a reciprocable member, means for reciprocating said member, means pivotally associated with said

member and movable therewith, a pair of ram rods pivoted to said pivotally associated means and movable therewith, and means for rotating said pivotally associated means relatively to said member about the axis of reciprocation of said member.

24. In a ramming machine, a pair of spaced ram rods simultaneously reciprocal, means for automatically reciprocating said rods, means for moving said rods to successive circumferential positions about an axis in space intermediate and parallel the line of reciprocation of said rods, and means for substantially equalizing the effective ramming pressure of said rods.

25. In a ramming machine, a pair of spaced ram rods, means for imparting reciprocatory motion to said rods in the direction of the length thereof, means including a pivot connection between said motion imparting means and rods for adjusting said rods to inequalities in a surface being rammed, and means for moving said rods to successive circumferential positions about an axis in space intermediate of and parallel to said rods.

26. In a ramming machine, a plurality of peens, means for projecting said peens simultaneously toward a surface of material to be compacted, means for substantially equalizing the effective ramming pressure of said peens, and means for moving said peens to a plurality of positions over the surface to be compacted in substantially circular paths.

In witness of the foregoing I affix my signature.

E. D. PATTERSON.
